Specification for Design.

Patented Nov. 14, 1916.

Application filed September 18, 1916. Serial No. 120,905. Term of patent 7 years.

To all whom it may concern:

Be it known that I, **WILLIAM MARK MUCHOW**, a citizen of the United States, residing at Evanston, in the county of Cook and State of Illinois, have invented a new, original, and ornamental Design for a Tooth-Cleaner, of which the following is a specification, reference being had to the accompanying drawing, forming part thereof.

Figure 1 of the drawings is a side elevation of a tooth cleaner, showing my new design. Fig. 2 is an end elevation of the same, and Fig. 3 is a plan thereof.

I claim:

The ornamental design for a tooth cleaner, as shown.

WILLIAM MARK MUCHOW.
